UNITED STATES PATENT OFFICE.

NICKOLAI TORMOEN AND JOSEPH TORMOEN, OF TAYLOR, WISCONSIN.

GEAR-SHIFTING MECHANISM.

1,274,632.

Specification of Letters Patent.

Patented Aug. 6, 1918.

Application filed June 25, 1917. Serial No. 176,859.

To all whom it may concern:

Be it known that we, NICKOLAI TORMOEN and JOSEPH TORMOEN, citizen of the United States, residing at Taylor, in the county of Jackson, State of Wisconsin, have invented a new and useful Gear-Shifting Mechanism, of which the following is a specification.

The subject of this invention is an **H** plate for automobiles, and the objects of the invention are, first, to provide means for automatically locking the lever in neutral position, second, to provide an automatically set clutch lever opened lock, third, to provide a simple and efficient locking **H** plate.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

One practical embodiment of the invention is shown in the accompanying drawing, wherein:

Figure 1 is a side elevation of the device held in unlocked position by the lever.

Fig. 2 is a plan view of the device with the top plate removed.

Fig. 3 is a cross section taken on the line 3—3 of Fig. 2.

Referring to the drawing by numerals:

In carrying out the invention we prefer to make use of an ordinary **H** plate 1 which is formed with depending ears 2 which are apertured to permit the plate to be secured in place in the usual manner. Upon the

plate 1 is secured by screws or otherwise, a plate 3 which is formed with an **H** registering with the **H** of the plate 1. Plate 3 is formed with a depending rib 4 at each end which serves to keep the plates spaced apart.

A shaft 5 depends from one side of the plate 1 and turns in the plates 1 and 3. A crank 6 is secured to the shaft 5 and oscillates between the plates 1 and 3. The crank 6 is provided with a through pin 7 which pivotally connects companion links 8, only one of which is shown, to the crank. The other ends of the links 8 are pivotally connected to one side of an irregular **H** plate 9. Plate 9 is slidable between the plates 1 and 3 and is formed with an **H** adapted to register, when in one position, with the **H**

of the plates 1 and 3. The plate is also provided with a cut away portion 10 which extends laterally from the **H**. A recess 11 may be provided in the plate 9 for the reception of a stud 12 which extends between the plates 1 and 3 and serves as a guide for the plate 9.

A crank 13 is secured to the lower end of the shaft 5, and the crank is provided with a pin 14. A connecting rod 15 has pivotal engagement with the pin 14.

A **Y** arm 19 has its arms straddling and secured to the upper end of the clutch lever 23, as shown, and rises therefrom. The standing leg of the **Y** arm is apertured to receive the rod 15 which is slidable in the aperture. A coiled spring 17 surrounds the rod 15 and is confined between the arm 19 and a collar 18 which surrounds the rod 15 adjacent its pivoted end. The free end of rod 15 is threaded to receive a nut 20 which may be clamped in any desired position on the threaded portion of the rod 15 by a jam nut 20'.

A bracket 16 is attached to the clutch pedal shaft, bracket, or other suitable part, and in the bracket the lower end of the shaft 5 is journaled.

In practice the device is operated in the following manner: The plate is attached to the car as usual and the **Y** arm 19 and bracket 16 attached as hereinbefore set forth. Considering principally Fig. 1, the gear shifting lever 21 is in one of the legs of the **H**, say intermediate speed. The crank 6 is turned to the position shown in Fig. 2 with the **H** of plate 9 registering with the **H** of the other plates. With the parts in this position the spring 17 is compressed between the collar 18 and the **Y** arm 19.

We now have the parts in their normal position during a straight run of the car.

Release of the clutch will draw the **Y** arm 19 forward into contact with nut 20 and hold the parts in the position just described so that lever 21 may be thrown through neutral to any desired position.

Should the operator, however, through inadvertence or otherwise, release the clutch lever, whereby the clutch automatically springs into operative engagement, and if the lever 21 should be in neutral position, the rod 5 will be rocked by means of the spring and crank, and through the connection of the rod 5 and plate 9 will slide said plate so that the projections 22 will close

the legs of the **H** slot, thus preventing the lever from being shifted as long as the clutch remains in engagement. Upon again releasing the clutch the plate 9 is moved to the position shown in the drawing, when the lever 21 may be moved to any desired point.

Having described our invention, what we claim as new and desire to secure by Letters Patent, is:

10. 1. The combination with an **H** plate and a lever associated therewith, of a plate slideable on the **H** plate, resilient means for sliding the latter plate to cover the legs of the **H** when the lever is in neutral position, and clutch lever operated means for sliding the plate to uncover the legs of the **H**.
2. The combination with an **H** plate, of a plate slideable thereon, said latter plate provided with an **H** opening registering in one position with the opening of the **H** plate, a shaft depending from the **H** plate, a crank on the shaft and connected to the sliding plate, resilient means for rocking the shaft to slide the plate to close the ends of the legs of the **H**, and clutch lever operated means for sliding the plate to uncover the legs.
25. 3. The combination with an **H** plate, of

another plate overlying the first plate and spaced therefrom, a locking plate sliding between the plates, resilient means for throwing the plate to locking position, and clutch lever operated means for sliding the plate to unlocking position.

4. The combination with an **H** plate, of another plate overlying the **H** plate and spaced therefrom, a locking plate sliding between the plates, a shaft journaled in the first mentioned plates and depending therefrom, a crank on the shaft connected to the locking plate, a crank on the lower end of the shaft, a rod pivotally secured to the latter crank, resilient means for throwing the locking plate to locked position, and an arm slideable on the rod and adapted for attachment to a clutch lever to throw the plate to unlocked position.

In testimony that we claim the foregoing as our own, we have hereto affixed our signatures in the presence of two witnesses.

NICK TORMOEN.
JOSEPH TORMOEN.
